UNITED STATES PATENT OFFICE

2,160,304

EXTENSION RULE

Frederick O. Carlson, New York, N. Y., assignor to
 Master Rule Manufacturing Company, Inc.,
 New York, N. Y., a corporation of New York

Application November 6, 1937, Serial No. 173,135

4 Claims. (Cl. 33—161)

This invention relates to improvements in extension rules and particularly with relation to the joint members by means of which the individual rule sections are secured together so as to permit relative longitudinal or sliding movement.

An important object of this invention involves the construction of the joint members and the manner in which they are attached to the rule sections so as to increase the usefulness of the rule and eliminate a present large source of breakage resulting from constructions now commonly employed.

A further object of the invention is the provision in extension rules of joint members interconnecting the rule sections in such manner that under excessive abuse or strain the rule sections may separate without breaking or destroying them so that they may be readily reassembled by the user at no cost to him and without necessitating their return to the manufacturer for repair.

A more specific object of the invention is to provide joint members of this type which have a spring or snap action in holding them attached to the rule sections.

Another specific object of the invention is the provision of a combination in an extension rule of a plurality of wooden rule sections interconnected by joint members which have at least one portion which has a spring or snap association with one of each pair of associated rule sections whereby under undue strain they may become separated without breakage of the wooden rule sections.

Other and more specific objects will be apparent from the following detailed description when taken in connection with the attached drawing.

This invention resides substantially in the combination, construction, arrangement and relative location of parts, all in accordance with the following disclosure.

In the accompanying drawing,

Figure 1 is a side elevational view of an extension rule constructed in accordance with this invention showing one section partly extended.

Figure 2 is an enlarged detailed view of two adjacent sections with their connecting joint members.

Figure 3 is a cross-sectional view taken on the line 3—3 of Figure 2.

The extension rule illustrated in the drawing is of the type commonly known and employed extensively in the industries at the present time. It comprises, as illustrated, a plurality of wooden

rule sections 1, which are generally rectangular in cross-section and all of which are of uniform length. Thus when all of the sections are completely retracted the rule forms a substantially regular rectangle. Each section 1 is provided along each side edge with a groove running throughout the length thereof which may be of any desired cross-sectional form, as for example rectangular, as illustrated. The two terminal sections at their free terminal ends are provided in accordance with common practice with metal protecting tips 2 which are preferably made of spring or tempered brass and attached thereto by reason of their resiliency and an adhesive, if desired.

The remaining ends of the terminal sections and both ends of all of the other sections, are provided with the joint members which are directly concerned with the subject matter of this invention. These joint members comprise, generally speaking, a pair of oppositely facing channels formed from a single piece of spring or tempered brass or other suitable material. As illustrated in the drawing, one of the channels comprises a bottom wall 4 which lies under the rule section at the end and a pair of side walls or flaps 5 which lie along the adjacent sides of the rule sections. The other channel section has a base wall which is an extension of the wall 4, and a pair of downwardly projecting side walls 7, the free edges 8 of which are inturned at right angles to lie in the grooves 3. As is quite common in this art, these joints have in addition to the construction illustrated and described, additional features of construction with which we are not here concerned, such as ears or tabs for positioning them on the rule sections and various forms of catches for holding the extensions in fully closed and open position.

The feature of this invention consists in the manner in which the side walls 5 are attached to the rule sections. It may be noted that it is common practice at the present time to strike out all these side walls and turn inwardly small ears which are bent over the adjacent side of the groove 3. This tab or ear may be thus locked around one of the sides of the groove forming an interlocked connection therewith. A very common result of this construction is that when the rule is unduly strained or abused, that is to the extent that the rule section pulls out of the joint member, the side wall of the groove is broken off because of the strong interlocking connection resulting from the inturned tab. This necessitates returning the rule to the manufacturer, making it

unavailable for use to the owner, and necessitating an undesirable expense to him. Indeed the only way that the rule may then be repaired is to substitute for the broken section an entirely new one. Quite frequently the joint member is also damaged requiring its replacement. Since the cost of repair relative to the total original cost of the rule must be kept low, this type of work is a source of annoyance and loss to the manufacturer 10 who cannot readily charge the full value of the service rendered.

This problem has been solved by means of the construction herein employed wherein, as clearly illustrated in Figure 3, the side walls 5 are bent 15 or crimped as indicated at 6, into the grooves 3 at the ends of the side walls or, where a stronger joint is required, throughout their length, to form a resilient inner lock which is adequate for all 20 normal purposes. The resulting rule is a reasonably strong structure adapted to all of the normal requirements thereof. The clamping action is aided by reason of the fact that an inherent resilient material is used to fabricate the joint members.

25 However, because of the construction employed, when the rule is actually strained, or is abused, the wood sections may separate from the joint members by reason of the fact that the crimped in portions 6 may slide over the adjacent side 30 walls of the grooves without breaking or destroying them. Thus this type of joint protects the rule sections and adds the highly desirable feature that strains and abuse may be relieved in a manner that does not permanently injure the 35 rule. The owner of the rule may himself quickly and readily repair it by simply forcing the separated section back into the associated joint member and forcing the side walls back into place, as for example by means of a blunt chisel, the end 40 of the screwdriver, and the like. The result is that such a repair may be made immediately and the rule put back into use without any expense to the owner.

45 From the above description it will be apparent to those skilled in the art that the structure by means of which the objects of this invention are attained may be varied by those skilled in the art without departure from the novel scope of the invention herein disclosed. I do not, therefore, 50 desire to be strictly limited to the disclosure as given for purposes of illustration, but rather to the scope of the claims granted me.

What I seek to secure by United States Letters Patent is:

1. A rule of the type described comprising a plurality of sections each comprising a rule length having grooves along the sides thereof and 5 joint members for interconnecting associated pairs of sections, each joint member having portions folded into the grooves of one of the sections of a pair and planar portions having projections resiliently and releasably gripping the 10 other section of the pair.

2. An extension rule comprising a plurality of substantially rectangular rule lengths having grooves along the sides thereof and a plurality of 15 joint members for interconnecting the adjacent ends of associated pairs, said joint members each comprising a channel having its side walls folded into the grooves of one section of one pair and planar portions having V-shaped indentations 20 releasably gripping the other section of the pair in the grooves.

25 3. An extension rule comprising a plurality of substantially rectangular rule lengths having grooves along the sides thereof, and a plurality of joint members for interconnecting the adjacent 30 ends of associated pairs, each joint member being made of a single piece of resilient metal and formed into a pair of oppositely facing channels, the side walls of one channel being folded around into the grooves of one section of each pair and providing interlocking, sliding engagement therewith, and the side walls of the other channel being depressed into the grooves of the other section of the pair to releasably clamp it therein.

35 4. An extension rule comprising a plurality of substantially rectangular rule lengths having grooves along the sides thereof, and a plurality of joint members for interconnecting the adjacent 40 ends of associated pairs, each joint member being made of a single piece of resilient metal and formed into a pair of oppositely facing channels, the side walls of one channel being folded around into the grooves of one section of each pair and providing positive, sliding engagement therewith, and the side walls of the other channels lying 45 against the side edges of the other section of the pair and having portions depressed into the grooves thereof, so as to resiliently and releasably hold the section therein.

50 FREDERICK O. CARLSON.
